FLUID MONITORING INSTRUMENT OR THE LIKE

Joseph Alan Huntsman, Broomall, Pa., assignor to
Pro-Tech, Inc., Springfield, Pa., a corporation of
Pennsylvania

Filed Apr. 17, 1964, Ser. No. 79,562

Term of patent 14 years

(Cl. D52—6)

Fig. 1.

Fig. 2.

FIG. 1 is a front perspective view, from above and to the right of center, of a fluid monitoring instrument or the like showing my new design;

FIG. 2 is a view of the same instrument in front elevation; and

FIG. 3 is an enlarged perspective view of the panel portion of the instrument.

The left side and bottom surfaces (both not shown) are mirror images of the right side and top surfaces, respectively, shown in FIG. 1; the rear surface (also not shown) is also plain and flat. The dominant features of the design reside in the portions shown in full lines.

I claim:

The ornamental design for a fluid monitoring instrument or the like, as shown and described.
